TORTILLA SERVING DISH

Richard De La Rosa, Hacienda Heights, Calif., assignor to ETL Corporation, San Jose, Calif.

Filed July 2, 1971, Ser. No. 159,161

Term of patent 14 years

Int. Cl. D7—01

U.S. Cl. D7—17

Fig. 1

Fig. 2

Fig. 3

Fig. 4

FIG. 1 is a top plan view of a tortilla serving dish showing my new design;

FIG. 2 is a side elevation view thereof;

FIG. 3 is an exploded isometric view thereof on a reduced scale; and

FIG. 4 is a bottom plan view thereof on a reduced scale.

I claim:

The ornamental design for a tortilla serving dish, as shown.
